LOUIS STEINBERGER, OF BROOKLYN, NEW YORK.

DISK STRAIN-INSULATOR.

1,160,546.

Specification of Letters Patent. Patented Nov. 16, 1915.

Application filed January 3, 1913. Serial No. 739,989.

To all whom it may concern:

Be it known that I, LOUIS STEINBERGER, residing at Brooklyn, in the county of Kings and State of New York, have invented certain new and useful Improvements in Disk Strain-Insulators, of which the following is a specification.

This invention relates to strain insulators, and particularly to those of the disk type.

10 A particular object of the present invention is to provide a new and improved insulator of this type wherein the irregularities of surface, for providing water sheds and for otherwise increasing the insulating 15 value of the disk without increasing the size of the disk, are arranged in such manner that they are amply supported from the body without material increase in the thickness of the intervening web portions of the 20 disk beyond what would be required for resistance against puncture.

A further object is to provide a structure as above, which comprises ridges formed on the surface of the disk so shaped that a materially greater proportion of the strength 25 of the ridges themselves, than is found in the ordinary concentric ridges, is employed to reinforce the web portions.

30 A further object is to provide a disk with ridges so shaped as to comprise relatively straight legs running tangent to the center of the disk, and forming angles, whereby the strength of the ridges is employed for reinforcing intermediate web portions.

35 A further object is to provide a disk with ridges on its opposite surfaces, and to shape the ridges in such manner that portions thereof upon the respective surfaces will lie in intersecting planes for lending added 40 strength to the structure.

A further object is to provide an insulator comprising a body portion and an annular flange extending therefrom having ridges on its surface, to provide a conductor projecting from the body portion, having a greater width in one diametrical direction than in another, and to form the ridges upon the surface of the disk to encircle the body so that portions of the ridges in the line of the 50 greatest diametrical width of the conductor are spaced a relatively greater distance from the body than are portions of the ridges in the line of less diametrical width of the conductor, whereby to prevent localized dis- 55 charges.

A further object is to provide a structure as above, which is simple in design, which comprises a minimum of material, and which is therefore cheap to manufacture, but is nevertheless thoroughly substantial 60 and embodies maximum efficiency, both as to its insulating qualities and as to its mechanical strength, for a given sized disk.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention: Figure 1 is a top plan view of an insulator constructed in accordance with the principles of this invention; Fig. 2 is a transverse sectional view partly in elevation, said section being taken substantially on the plane of line 2—2 of Fig. 1; and Fig. 3 is a view similar to Fig. 2, but illustrating a modification.

Referring to the drawings for a more detailed description of the structure illustrated, the numeral 1 indicates what may be termed the body portion of the insulator, which portion is preferably of a more or less elongated cylindrical shape adapted for receiving the strain members illustrated at 2 and 3.

The strain members illustrated each comprise a short bolt having an eye as 4 at its outer end, and having its inner end formed as a head 5 as clearly disclosed in Fig. 2. The inner ends of the two strain members are spaced apart and the material of the body fills the intervening space for effectually insulating the members from each other. 100

It will be understood, that though I have shown and described the strain members as comprising simple bolts having heads spaced apart and molded within the body 1 in axial alinement, said strain members may of course take any other form described for increasing the mechanical strength of the structure in resisting strains placed upon the strain members, or for increasing the insulating value of the structure. 110

The disk portion of the structure is illustrated generally by the reference numeral 6, and will be hereinafter referred to as the web. It comprises a wall or annular flange of substantially uniform thickness springing from the body 1 preferably about midway between the ends of the body, and serving, in addition to its insulating quality, as a continuous bond between the system of reinforcing ribs or ridges now to be described.

Formed upon the upper surface of the web 6 is a plurality of ridges designated as 7, 8 and 9. These ridges encircle the body portion 1, but they are not circular as has been heretofore customary. Each of them comprise four substantially straight legs joined by angles forming a square, the square or ridge 7 being smallest and nearest the body 1, the square or ridge 8 being larger and spaced equidistant from all sides of the square or ridge 7, and the square or ridge 9 being successively larger and surrounding the ridge 8. The legs of the squares may be 25 slightly bowed, if desired, as indicated in the ridge 9. As many squares or ridges may be employed as desired for larger insulators, or more or less of the squares or ridges may be employed upon a given sized insulator.

It will be noted that the intermediate portion of the length of each of the straight legs of the squares, is relatively nearer the body 1 than are the ends of the legs or the angles connecting the legs together. The legs of the squares stand tangent to circles drawn concentric with the body 1, and the result is that forces tending to fracture the web, especially such forces as may be exerted against the upper or lower surface of the web, would need to contend with the reinforcing value afforded by the fact that the intermediate portions of the legs, standing as they do close to the body 1, are quite rigidly supported from the body 1, only a short expanse of the web portion 6 intervening, as along a line A—A in Fig. 1, (the short expanse of web obviously affords materially greater strength than would a longer expanse such as appears between the body 1 and the end portions of the legs) and the opposite end portion of the legs therefore afford substantial braces extending across the surface of the web to a considerable distance from the body 1, so as to provide an effectual reinforcement for the outer portions of the web.

A line, as B, drawn concentric to the center of the body 1, and intersecting one of the angles of a square will approach or intersect, according to the distance between the ridges, the next outer ridge intermediate the length of the legs of said next outer ridge. This outer ridge is therefore effectually reinforced from the inner ridge. The natural tendency of the web to break along a line substantially

concentric to its central body 1 is overcome, and material strength is given the structure in addition to what would be inherent to the ordinary circular or concentric ridges. The legs illustrated, being substantially straight, 70 they act as straight strengthening bars and as such constitute a greater resistance to force of lateral strains than would the circular or concentric ridges or bars ordinarily employed. 75

It will, of course, be apparent that the same principles may be embodied by shaping the ridges to form other figures than squares. Any figure having substantially straight legs will be productive of reinforcing value 80 greater than that of circular ridges. The spaced individual square figures illustrated, however, are at this time thought to be preferable.

Beyond the ridge or square 9 there is preferably arranged a circular ridge or flange 10 formed substantially concentric to the body 1 and adapted to coöperate with a similar ridge formed upon the opposite surface of the web to form an annular groove 11 encircling the periphery of the web. 85

The opposite surface of the web is provided with ridges 12 in all respects the counterpart of those just described.

The ridges upon the two surfaces of the web may be arranged directly opposite each other, but they are preferably arranged so that the straight legs of those on one surface stand in longitudinal planes intersected by the longitudinal planes of those on the other surface for lending added strength to the structure. In insulators having their ridges forming a square figure as illustrated, the squares of one surface are turned substantially 45° relatively to the squares of the other surface, as shown by the dotted line in Fig. 1, so that the ridges of one surface lap the ridges on the other surface in angular relation. The intermediate portions of the squares upon one surface are supported and reinforced by thelapping angular portions of the squares upon the other surface of the web. 100

The substantially parallel legs of adjacent squares upon one surface define a straight line of weakness longitudinally between them, as for instance along lines X—X and Y—Y of Fig. 1. These lines are effectually reinforced however, not only by the adjacent portions, as 15, of the other legs of the squares, but especially by the angular portions, as 16, of the squares upon the other surface of the web. Reference to Fig. 1 shows that these portions 16 form angular reinforcing parts practically extending between and connecting the intermediate portions of the legs, and this is true in every instance with respect to both sides of the web. 115

The strain members 2 and 3 are preferably arranged so that the diameter of great 120 125 130

est measurement lies in a plane extending toward opposite angles of the squares upon the respective surfaces of the web so that the relatively projecting portions of a given strain member will be properly spaced from a given ridge. The tendency of localized discharges between the strain members is thus minimized. This is especially true where the ridges upon the opposite surfaces are arranged in intersecting planes as shown in Fig. 1 for the reason that in such a structure the strain members are likewise rotated relatively to each other.

All ridges upon the two surfaces of the web may project outward from the surface of the web for a uniform distance, and the body 1 may project from the surfaces of the web for a like distance, and also the thickness of the web itself may be uniform throughout, if desired. It is, however, apparent that these various proportions may be altered within the scope of the invention, for instance, as shown in the modification Fig. 3 wherein the body 1 projects for a slight distance beyond the plane of the outer edges of the ridges, and wherein the thickness of the web is slightly greater nearer the body 1 and gradually decreasing in thickness toward its periphery. The tendency to puncture of the web nearest the body 1 is, of course, greater than at points further spaced from the body. The difference in thickness of the web, as shown in Fig. 3, may be calculated so as to compensate for the difference in tendency to puncture. For the same reason the degree of prominence of each of the ridges, that is the distance they project from the surface of the web, may be successively reduced as shown in Fig. 3. This figure also indicates the outer circular ridge 10 as being sufficiently wide to effectively protect the intermediate ridges. The outer lateral edges of the ridges 10 are in the plane substantially the same as the plane of the corresponding edges of the innermost ridge.

In Fig. 3 also there is illustrated a groove as 12 formed in some of the ridges. These grooves, where employed, are formed at the apex of the ridges and preferably extend throughout the length of the ridge. They serve to further increase the surface extent of the structure and to form positive paths for conducting away such moisture as happens to flow to the apex of the ridge. They prevent the moisture from flowing directly across the ridge.

As many changes could be made in this construction without departing from the scope of the following claims, it is intended that all matter contained in the above description or shown in the accompanying drawing shall be interpreted as illustrative only and not in a limiting sense.

Having thus described my invention what

I claim as new and desire to secure by Letters Patent, is:—

1. An insulator, comprising a web of insulating material formed with a plurality of ridges on each of its two opposite surfaces, each of said ridges having portions of its length lying relatively nearer the center of the web than other portions of the ridges, and the portions of the ridges of one surface of the web which lie farthest from the center of the web, being disposed to overlie portions of the ridges on the other surface of the web which lie nearest the center of the web, whereby to reinforce the web.

2. An insulator, comprising a web of insulating material, a conductor disposed upon one surface of said web, said conductor having a part projecting relatively farther from the center of said web than other parts of said conductor, and a ridge upstanding upon the mentioned surface of the web surrounding said conductor, said ridge having a portion intermediate its length spaced farther from the center of said web than portions at other points in the length of the ridge, and the portion of the ridge which is spaced farther from the center of the web being radially opposite that portion of the conductor which lies farthest from the center of the web, for the purpose described.

3. An insulator, comprising a web of insulating material, ridges formed upon the opposite surfaces of said web, the ridge upon one surface of said web being shaped to form a poly-sided figure, the ridge upon the other surface of the web also being shaped to form a poly-sided figure, and the poly-sided figures on said two surfaces being disposed so that each of the sides of one of said figures overlie one of the sides of the other figure, and said overlying sides extending in angular relation to each other, substantially described.

4. An insulator, comprising a web of insulating material, ridges formed upon each of the opposite surfaces of said web, said ridges each being formed into a relatively straight portion and a relatively angular portion, and the relatively angular portion of the ridge on one surface being disposed to overlie the relatively straight portion of the ridge on the other surface, whereby to reinforce the web.

5. An insulator, comprising a web portion, a pair of ridges outstanding upon one surface of said web spaced apart, a ridge outstanding from the opposite surface of said web having portions spaced apart in the length thereof overlying each of said first ridges, so as to reinforce said first ridges, and all of said ridges extending in a direction entirely surrounding the central portion of the web.

6. An insulator, comprising a web portion, a pair of ridges outstanding upon one

surface of said web, spaced apart, and a ridge outstanding upon the opposite surface of said web having a portion intermediate its length overlying one of said first ridges, 5 and having portions in its length at opposite sides of said intermediate portion extending along the surface of said web in diverging relation and overlying the other of said first ridges, so as to reinforce said first 10 ridges.

7. An insulator comprising a member of insulating material having a conductor part at one surface thereof, said conductor part having a portion projecting laterally from 15 the main body thereof, and a ridge formed upon the mentioned surface of the insulat-

ing material surrounding said conductor part, said ridge having a portion intermediate its length spaced farther from the main body of the conductor part than portions 20 at other points in the length of the ridge, and the portion of the ridge which is spaced farther from the main body of the conductor part being radially opposite that portion of the conductor part which projects farthest 25 from the main body thereof.

In testimony whereof, I affix my signature in the presence of two witnesses.

LOUIS STEINBERGER.
